WILLIAM H. BRUMLEY, OF PORTLAND, OREGON, ASSIGNOR TO AIRO MANUFACTURING CO., OF PORTLAND, OREGON, A CORPORATION OF OREGON.

HYDROCARBON-OIL-GAS BURNER.

1,097,525.

Specification of Letters Patent.

Patented May 19, 1914.

Application filed April 15, 1913. Serial No. 761,389.

To all whom it may concern:

Be it known that I, WILLIAM H. BRUMLEY, a citizen of the United States, and a resident of the city of Portland, county of Multnomah, State of Oregon, have invented a new and useful Improvement in Hydrocarbon-Oil-Gas Burners, of which the following is a specification.

My invention relates to oil burners and 10 has for its main objects the providing of a burner in which the intensity of the flame may be positively controlled, which will promote more perfect combustion, and which will avoid any wasteful feed of the oil.

15 A further object of my invention is to provide a burner in which the flames are constantly directed away from the body of the burner, instead of the latter being continually enveloped in the flames, as is commonly 20 the case among other types of burners.

I attain such objects by causing the proper intermixing of air with vaporized oil. I, furthermore, use an improved retort designed to allow for the expansion of the 25 heated vapor and thereby effectually overcoming the fitful or irregular feed of the oil vapors, an objectionable feature common to nearly all oil burners. I further arrange the parts so as to prevent the retort from being 30 intensely heated, and thereby avoid the formation of carbon compounds on the interior of said retort, an objectionable feature also common to all types of oil burners.

The details of my improvements are hereinafter fully set forth.

In the accompanying drawings: Figure 1 is a side elevation of my oil burner; the pan located beneath the body of said burner is shown in section so as to illustrate the manner in which the pan and body are held together; Fig. 2 is a vertical longitudinal section of my burner, taken approximately on the line indicated by 2-2 in Fig. 3; Fig. 3 is a transverse vertical section taken approximately on the line 3-3 of Fig. 1; and Fig. 4 is a horizontal sectional view of the retort taken approximately on the line 4-4 of Fig. 1.

The body, *a*, comprising the mixing chamber of my burner, is tubular in form, the sides and front end of said body being convexed outwardly. Burner slots, *b*, cut into said convexed portions provide an outlet for the gases intermixed in said chamber. By 55 cutting these slots divergent, the sheets of

gases issuing through said slots will be converged, and thereby a better flame body is formed. The rear end of this body is tapped to accommodate the seating of a nipple *c*. The inner periphery of this nipple is threaded and an outer pipe, *d*, extending to the forward part of the body, *a*, is screwed in such threaded portion. The nipple, *c*, is counter-tapped and an inner pipe, *e*, screwed therein, extends inside the pipe, *d*, about three-quarters the length of the latter. A segmental air inlet slot, *f*, (see Figs. 2 and 3) provided in the nipple, *c*, opens into the lower portion of the annular space between the two pipes *d* and *e*. Rigidly attached to 60 the base of the body, *a*, by the screws, *g*, is a pan *h*.

The retort, *i*, is provided with a lug *j*, bearing on the upper side of the body *a*, and a lateral web *k*, which bears on the slightly 65 protruding end of the nipple *c*, and is bolted to the rear end of the body, *a*, by the bolts *k'*. See Figs. 1, 2 and 3. These two bearing points support said retort rigidly with respect to the body *a*. Furthermore, the rear 70 end of the retort, *i*, is provided with the laterally extending ears *m*, by means of which the retort is bolted to the face-plate *n*. Said face plate corresponds to the door of an ordinary stove inside of which my 75 burner has been installed. The foremost portion of the retort, *i*, is provided with a projecting boss *o*, into which is tapped a branch pipe *p*.

The feed pipe *r*, bearing in the face plate 80 *n*, extends longitudinally the length of the body *a*, its forward end being closed with a cap *r'*. A T-section *s* forms a convenient connection between said feed pipe *r* and the branch pipe *p*. The feed pipe *r* connects 85 directly with the storage tank (not shown) by the conduit *t*; the flow through said conduit being controlled by a manually operated needle valve *u*.

In the rear end of the retort, *i*, is a vertically projecting boss *v* (see Figs. 1 and 2) into which is tapped a pipe *w*. Said pipe *w* projects upward above the bottom of said retort, in the manner of a stand pipe. Threaded into the lower end of the pipe *w* 105 is a globe-valve *x*. The port *y* of this valve is axially coincident with the pipe *e*, and is so located that a fluid under sufficient pressure will be discharged through the port *y* directly into the open pipe *e*. However, if 110

the fluid is not under sufficient pressure it will flow normally out of said port into the pan *h*. A needle *z*, operated by the handle *5*, controls the flow through the port *y*. The handle, *5*, is made preferably of wood, or other heat insulating material, and is provided at its upper end with a flange *6*, to prevent the operator's hand from coming in contact with the heated metal needle bar *7*.

10 The method of operating this burner is as follows: The valve, *u*, is opened, thereby allowing the oil under pressure to flow into the feed pipe *r*. After said feed pipe has been completely filled, the oil will rise in the 15 branch pipe *p* into the retort *i*. When the level of the stand pipe, *w*, has been reached, the oil will overflow into the valve *x*, which, having been previously opened, will allow the oil to flow through the port *y* into the 20 pan *h*. After a small amount of oil has been discharged into the pan *h*, the oil valve, *u*, is closed and said oil ignited. The resultant flame will burn up around the feed pipe *r* and the retort *i*, thereby heating the oil contained therein and causing the same to be 25 vaporized. The resultant expansion will exert a pressure on the flow through the port *y*, thereby causing said flow of vaporized oil to be directed into the pipe *e*, instead of allowing same to flow into the pan *h*. The 30 forced feed of vapor through the pipe *e*, thence through the pipe *d* will create a suction through the segmental slot *f*, thereby drawing a certain amount of air into the mixing chamber of the body *a*. The resultant gas escaping through the slots *b* will be 35 ignited, thereby further heating the retort *i*, and continuing to vaporize the oil contained in said retort. After this oil has been 40 completely vaporized, the flames through the slots *b* will tend to die down, upon which action the operation will again open the oil-valve *u*. The retort, *i*, will then have been heated sufficiently to vaporize the oil 45 discharged into it, and said vapor being constantly under pressure will supply a forced feed through the valve *x* into the pipe *e*.

By having the feed pipe extend to the length shown in Fig. 1, I provide a means 50 for facilitating the starting of a fire, for the oil in this length of pipe being heated, will tend to vaporize and the consequent expansion will place an increased pressure on that oil delivered to the retort *i*.

55 In order to overcome the objectionable feature of the oil "breathing" in the retort, I have made the cross-sectional area of the latter vary directly as the expansion of the vapor. This "breathing" is a fitful 60 flow of the oil instead of a steady one, and I have found that by varying the shape of my retort, as previously described, the objection will be entirely overcome, and the feed will be continuous and uniform.

65 Another advantage in having the pipe, *w*,

extend upwardly in the retort is the fact that the most completely gasified vapor will be delivered to the mixing chamber. By locating the air slot, *f*, as previously described, the air will be drawn into the mixing chamber in the form of a lower stratum. This air, being heavier than the gasified vapor, will tend to remain in the lower portion of said chamber, and will not mix readily with said gas, only sufficient oxygen being taken up by the gas to form a more perfect combustion. The flames of burning gas issuing from the slots, *b*, depend directly upon the amount of gas fed through the port *y* of the valve *x*, and therefore the amount of air 70 can be regulated by the operation of the valve handle *5*. The back pressure in the retort, *i*, when the valve *x* is partially or wholly closed, retards the flow of oil through the oil valve *u*. In this way, the 75 flow of oil is automatically controlled by the valve *x*, thereby making the control independent of the oil valve *u*.

I have found that the pipes, *d*, *e*, and the body, *a*, should be of an approximate relative proportion in order to obtain the best results. The length of said pipes effectually smothers any back-fire which might accidentally develop inside of the body *a*.

It is to be noted also that the flames do 90 not envelop the body, as is the case in all other burners within my knowledge. This feature insures protection against the burning up of the body, which objection is commonly found in the burners referred to.

I claim:

1. In a hydro-carbon burner, a retort, an oil-feed conduit from a head of oil into the retort; an elongated mixing chamber having a tube extending longitudinally 105 therein, such tube being open at its inner end, a second tube within the first mentioned tube, such inner tube being of smaller diameter and lesser length than the first mentioned tube, the inner tube being open at both ends and constituting the inlet to the mixing chamber, a supplemental air inlet between the two tubes; and a conduit from the retort, such conduit having a valve-controlled outlet located opposite to and 110 adapted for discharging the vaporized oil into said inner tube of the mixing chamber.

2. In a hydro-carbon burner, a retort, an oil-feed conduit from a head of oil into the retort, an elongated mixing chamber having a tube extending longitudinally therein, such tube being open at its inner end, a second tube within the first mentioned tube, such inner tube being of smaller diameter and lesser length than the first mentioned tube, the inner tube being open at both ends and constituting the inlet to the mixing chamber, a supplemental air inlet between the two tubes; and a conduit entering the outlet end of the retort and projecting above 120

the bottom of the latter, such conduit having a valve-controlled outlet located opposite to and adapted for discharging the vaporized oil into said inner tube of the mixing chamber.

3. In a hydro-carbon burner, a retort having an interior of increasing lateral cross section from its inlet to its outlet; an elongated mixing chamber having a tube extending longitudinally therein, such tube being open at its inner end, a second tube within the first mentioned tube, such inner tube being of smaller diameter and lesser length than the first mentioned tube, the inner tube being open at both ends and constituting the inlet to the mixing chamber, a supplemental air inlet between the two tubes; and a conduit from the retort, such conduit having a valve-controlled outlet located opposite to and adapted for discharging the vaporized oil into said inner tube of the mixing chamber.

4. In a hydro-carbon burner, a retort having an interior of increasing lateral cross section from its inlet to its outlet; an elongated mixing chamber having a tube extending longitudinally therein, such tube being open at its inner end, a second tube within the first mentioned tube, such inner tube being of smaller diameter and lesser length than the first mentioned tube, the inner tube being open at both ends and constituting the inlet to the mixing chamber, a supplemental air inlet between the two tubes; the retort being located over the mixing chamber.

ber and the latter having gas outlets at the top extending under the retort; and a conduit from the retort, such conduit having a valve-controlled outlet located opposite to and adapted for discharging the vaporized oil into said inner tube of the mixing chamber.

5. In a hydro-carbon burner, a retort having an interior of increasing lateral cross-section from its inlet to its outlet, a valve-controlled oil-feed conduit from a head of oil into the retort; an elongated mixing chamber having a tube extending longitudinally therein, such tube being open at its inner end, a second tube within the first mentioned tube, such inner tube being of smaller diameter and lesser length than the first mentioned tube, the inner tube being open at both ends and constituting the inlet to the mixing chamber, a supplemental air inlet between the two tubes; the retort being located over the mixing chamber and the latter having gas outlets at the top extending under the retort; and a conduit entering the outlet end of the retort and projecting above the bottom of the latter, such conduit having a valve-controlled outlet located opposite to and adapted for discharging the vaporized oil into said inner tube of the mixing chamber.
